United States Patent Office

Des. 196,535
Patented Oct. 8, 1963

196,535

BOTTLE

Pearl L. Schluttig, P.O. Box 7544, Washington 4, D.C.

Filed May 20, 1963, Ser. No. 74,977

Term of patent 14 years

(Cl. D58—8)

FIG. 1.

FIG. 3.

FIG. 2.

FIG. 1 is a top plan view of a bottle showing my new design;

FIG. 2 is a front elevational view thereof, the rear being substantially the same; and

FIG. 3 is a bottom plan view thereof.

I claim:

The ornamental design for a bottle, substantially as shown and described.
